CLAIM

The ornamental design for a massage appliance, as shown and described.

DESCRIPTION

FIG. 1.1 is a rear perspective view of a massage appliance showing my new design;

FIG. 1.2 is a front perspective view thereof;

FIG. 1.3 is a rear view thereof;

FIG. 1.4 is a front view thereof;

FIG. 1.5 is a right side view thereof;

FIG. 1.6 is a left side view thereof; and

FIG. 1.7 is a bottom plan view thereof.

The broken lines in the drawings depict unclaimed subject matter only and form no part of the claimed design.
